UNITED STATES PATENT OFFICE.

FRANK M. REYNOLDS AND GEORGE C. TEWKSURY, OF NEWARK, N. J.

ELEVATOR.

SPECIFICATION forming part of Letters Patent No. 280,670, dated July 3, 1883.

Application filed April 24, 1883. (No model.)

To all whom it may concern:

Be it known that we, FRANK M. REYNOLDS and GEO. C. TEWKSURY, of Newark, in the county of Essex and State of New Jersey, have 5 invented a new and useful Improvement in Elevators; and we do hereby declare that the following is a full, clear, and exact description of the same.

Our invention relates to improvements in 10 elevators, and more particularly to that class of elevators for which George C. Tewksbury obtained Letters Patent of the United States numbered, respectively, 255,049, 255,050, and 255,051. The general object of the construction 15 shown in these patents is to place the moving car under the complete control of an operator upon any floor of a building in which it is situated, so that the car can be started from any floor and stopped automatically at 20 any other floor, or at the extreme end of its route. The mechanism described in these 25 patents consisted, essentially, of a rod running the entire length of the elevator-well, and having at each floor of the building a radial 30 projection; of means for rotating this rod to bring any one of its projections in line with a 35 stud on the elevator-car; of an index so arranged in relation to the rod that the moving 40 of the pointer or lever to any particular number on a scale would cause the projection at 45 the floor corresponding to that number to be set in the path of the car; and, finally, of belt-shipping devices connected to the rod, and 50 means for operating such devices by moving the rod vertically, and thereby starting and 55 stopping the car, the movement of the rod in 60 starting the car being controlled by an operator at any floor, and that in stopping such 65 car being automatically accomplished when 70 the projection on the rod is struck by the stud 75 on the car. A suitable automatic brake mechanism is also employed. It is desirable to run 80 these elevators at as high a rate of speed as possible, and it has been found that under 85 some circumstances the car stops with a sudden 90 jolt and jar. This is particularly to be avoided in passenger-elevators, and it is the 95 principal object of the invention now to be described.

50 While the principle upon which our present invention operates is precisely similar to that of the patents referred to, we have materially

modified the construction. Instead of stopping the car by the direct blow of a stud against a projection on the rod, we have devised an independent stopping and starting mechanism located at one end of the elevator-well, but controlled, as before, by an operator at any story of the building.

Our invention therefore consists in combining with a car and suitable elevating mechanism a vertical rod having both a longitudinal and rotary movement, a lever, operating also as an indicator, connected to such rod, and an auxiliary stopping and starting device, 65 not upon but connected to such rod and operated by its movement.

It consists, moreover, in the peculiar construction, and in the various novel combinations of the operative parts, as fully herein- 70 after described and claimed.

In the drawings, Figure 1 is a side elevation. Fig. 2 is a plan view. Fig. 3 is an end view. Fig. 4 is a section on the line *y y*. Fig. 5 is a view of the indicator and starting-lever.

In these drawings the car, the driving shaft, and belt-pulleys, and the hoisting apparatus are not shown, as they are not essential to a proper understanding of this device, and are not materially different from those shown 80 in the patents referred to.

A⁶ is a rod running the entire length of the elevator-well. It is swiveled at the bottom in collars M M, so as to have a rotary motion, and is also mounted on a trunnion of the crank 85 G⁶, (hereinafter referred to,) so that it can move longitudinally.

A is a short auxiliary rod journaled in brackets, B⁶, attached to the frame-work. A long spur-wheel, B, is keyed to the shaft A, which 90 meshes with a pinion, T, on the rod A⁶, the wheel B being long enough to permit the extreme longitudinal movement of rod A⁶ without disconnecting the gears. At the bottom of the rod A is keyed a bevel-gear wheel, C.

D is a horizontal shaft, upon one end of which is splined a bevel-gear, C⁶, which meshes with the gear C on shaft A. The spline or feather permits the shaft D to slide freely.

Secured rigidly to the shaft D are radial projections E, extending in different directions and corresponding in number to the stations or stories of the elevator-well. These projections are arranged on the shaft at suitable in-

tervals between safety-collars F at the ends. In the drawings, Fig. 2, two only of such projections are shown.

I is a shaft extending parallel to shaft D, 5 and adapted to be driven in any suitable manner from the driving-shaft and to be set in motion when the belt is on the tight pulley. It is journaled in suitably-supported hangers K, and between such hangers is threaded for its 10 entire length. A nut, J, is mounted on this screw-shaft, and is caused to travel upon it, it being steadied by a guide-rod, X, passing through a guide, Y, on the nut. A radial projection, J', on the nut J strikes one of the 15 projections E on the shaft D as the nut travels along the threaded shaft and moves the shaft D forward.

The shaft D is connected to the belt-shipping rod in the following manner: R R are 20 transverse rock-shafts, Figs. 1 and 2, on which are keyed cranks G G, connected at their upper ends to the rod H, which, by a fork, D⁶, Fig. 2, operates the shipping-rod E⁶. The rod E⁶ is connected in any suitable manner, so as 25 to ship the belts from the tight to the loose pulley, and vice versa. It will now be readily understood that if the shaft D be connected to the transverse shaft R, so that its sliding movement will rotate the latter, such movement will 30 shift the belts and either stop or start the elevator, according to its direction. This connection is made by means of the segment O, keyed to one of the shafts R and engaging with the cylindrical rack N upon shaft D, Fig. 1—a 35 construction which permits the free revolution of the shaft D.

The mechanism described accomplishes the automatic stoppage of the elevator.

The devices for starting the car and placing 40 it under the control of the operator will now be described.

It was remarked before that the rod A⁶ was mounted on a trunnion of the crank G⁶. This crank is keyed to one of the shafts R, Figs. 1 45 and 3, so that the vertical motion of the rod will operate the belt-shippers. The devices for moving the rod are shown in detail in Fig. 5. A long pinion, 12, is keyed on the rod, with 50 which engages a segment, 13. The pivoted lever 9, which moves the segment, projects through a slot in the indicator-case, attached to the wall of the building near the door of the elevator, and can be moved horizontally along 55 a row of numbers on the case, which numbers correspond both to the number of floors and to the number of projections E on the shaft D; and these numbers and the connected mechanism are so arranged that if the lever be turned to a point opposite any one of them the 60 resulting motion of the rod A⁶ will, through the rod A and the bevel-gearing, bring the corresponding projection, E, on shaft D into the path of the nut J on shaft I. The elevator is now ready to start, and the mechanism for that purpose is also shown in Fig. 5.

A lever, 10, is pivoted to a hanger, 11, or in any other manner, its short arm being swiv-

eled to the rod A⁶ by a sleeve, 15, held between collars 14 on the rod, it being connected to the sleeve by a link, 16. This construction, 70 while it permits the rod A⁶ to rotate independently of the lever 10, also enables the operator to raise such rod, the effect being to raise the crank G⁶, rock the shaft R, and shift the belt to the tight pulley. Simultaneously 75 with the starting of the hoisting mechanism the nut J commences to travel along the shaft until it comes in contact with the projection E. The shaft D is moved forward and the shipping-rod impelled in the opposite direction by the rack-segment N O, gradually retarding the speed of the car, and finally stopping it altogether. The safety-collars F on shaft E are for the purpose of shifting the belt 80 and stopping the car at either end of the well 85 in case the projection E should break and the car continue its motion past the floor at which it should have stopped.

Having thus described our invention, what we claim as new, and desire to secure by Letters Patent, is—

1. In an elevator, the combination of the following elements: a moving car and proper hoisting apparatus, a vertical rod extending throughout the length of the well, indicating devices, means for rotating and moving longitudinally the said vertical rod, and an auxiliary connected mechanism controlled by the movement of said vertical rod, and so arranged in relation to the indicating devices 95 that the car will stop automatically at a predetermined station or floor.

2. In an elevator, the combination of a moving car and hoisting apparatus, a vertical rod having both rotary and longitudinal motion, 100 a traveling device operated by the driving-shaft and moving in a certain relation to the motion of the car, a sliding shaft connected to a belt-shipping rod and having projections corresponding to the floors in the building, 105 and an indicator connected to such shaft, to bring the projection corresponding to the determined stopping-place in line with the said traveling device, whereby the car is automatically stopped at the proper point.

3. Combined with a vertically-moving elevator-car, an auxiliary device traveling in a certain relation to the movement of the car, and arranged by a connected mechanism to stop such car at a predetermined point.

4. The combination, with the rod A⁶, having both sliding and rotary motion, of the sliding shaft D, having radial projections, the screw-rod I, connected to the driving-shaft, the traveling nut J, and the shipping-rod.

5. The combination, with the rod A⁶, of the auxiliary rod A, the shaft D, geared thereto, and having both a sliding and rotary motion, the radial projections E, the screw-rod I, the traveling nut J, the rock-shafts R, geared to 130 the shaft D, the cranks G, and the shipping-rod.

6. In an elevator, the combination, with the rod A⁶, journaled on a trunnion of the crank

G⁶, of the operating-lever 10 and the belt-shipping device.

7. In an elevator, the shaft D, having both sliding and rotary motion, in combination with 5 the shaft R, the segment O, the cylindrical rack N, the crank G, and the shipping-rod.

8. Combined with the elevator-car and means, substantially as described, for starting and stopping it, the safety-collars F on the 10 shaft D.

9. The driving-shaft of an elevator, hoisting apparatus, and a moving car connected thereto, in combination with an auxiliary de-

vice moving in a certain relation to the movement of the car and under external control 15 and regulation, whereby the movement of the car is controlled and regulated, substantially as described.

In testimony whereof we have signed our names to this specification in the presence of 20 two subscribing witnesses.
